TIME DELAY RELAY

Carl A. Schaefer, Milwaukee, Wis., assignor to
Square D Company, Detroit, Mich., a corpora-
tion of Michigan

Application March 24, 1952, Serial No. 278,283

16 Claims. (Cl. 161—1)

1

This invention relates to automatic timing mechanisms having adjustable time delay means for varying the operation of the mechanism; more specifically, this invention relates to an adjustable timing mechanism for the attainment of either a substantially linear relationship between the timed period and the setting of the controlling element, or other predetermined relationships, the timing period being the same regardless of from which direction a setting is made.

One object of the present invention is to provide an improved adjustable timing mechanism wherein the relationship between the delay time and the setting of the timing controller is substantially linear and is unaffected by "backlash," the term being used herein to indicate a difference in timing period when the same setting is made from opposite directions.

Another object of the present invention is the provision of an improved adjustable time delay relay in which the time delay is varied by varying the effective length of a timing groove through which the timing air flows.

Another object of the invention is the provision of an improved adjustable timing device in accordance with the preceding object in which a capillary timing groove is provided in one of a pair of closely mating surfaces, the timing air flowing through continuously adjustable lengths of the timing groove to effect the timing operation.

Another object of the invention is the provision of an adjustable timing device in accordance with the preceding object in which a pair of circular elements having closely mating surfaces are provided, one of the elements being rotatable and having a capillary groove therein and an aperture communicating the groove with the atmosphere, the other element having an aperture communicating its mating surface with the interior of the timing chamber and so positioned as to register with the timing groove as the rotatable element is rotated, whereby the effective distance of the timing groove through which the timing air must pass may be varied to determine the timed period.

Another object of the invention is the provision of an adjustable timing device employing flow of timing air through a timing groove of non-uniform cross sectional area to provide any desired relationship between the timing period and the setting movement, the effective length of the groove being continuously adjustable.

Other objects and features of the invention will be readily apparent to those skilled in the art from the specification and appended draw-

2

ings illustrating certain preferred embodiments in which:

Figure 1 is a front elevational view of an electrical relay incorporating the timing mechanism of the present invention.

Figure 2 is an enlarged sectional view along the lines II—II of Figure 1.

Figure 3 is a reduced sectional view along the lines III—III of Figure 2.

Figure 4 is a reduced sectional view along the lines IV—IV of Figure 2.

Figure 5 is a reduced sectional view along the lines V—V of Figure 2.

Figure 6 is a reduced sectional view along the line VI—VI of Figure 2.

Figure 7 is an enlarged sectional view along the lines VII—VII of Figure 6.

Figure 8 is a reduced sectional view along the line VIII—VIII of Figure 2.

Figure 9 is a view similar to Figure 4, with the parts differently positioned.

Figures 10 and 11 show modifications of the parts shown in Figure 3.

The device of the present invention comprises a valve base 1, having upper and lower chambers 10 and 20, respectively, therein. The upper portion of chamber 10 is closed by a cover 2 having holes 3 therein for permitting air to pass into the chamber 10, a filter 4 being interposed between the cover 2 and the valve base 1 to filter the incoming air. Extending through the central opening in the cover 2 is an upstanding shaft 5 of a valve wheel 6, the shaft 5 being joined by a pin 7 to a rotatable dial 8 which carries an index bearing dial chart 9.

As may be seen from Figure 4, extending through the valve wheel 6 about the central portion thereof are three large holes 12, the purpose of which will subsequently be explained; a single hole 11 extends through the valve wheel 6 near the periphery thereof. The lower surface (from the view of Figure 2) of valve wheel 6 is provided with a capillary timing groove 13 which, as shown in Figure 3, has one end communicating with the hole 11, and which extends in a generally circular path (with the center of rotation of the valve wheel 6 as the center) about 330 degrees, terminating in a circular indentation 14 which does not extend through the valve wheel 6.

The undersurface of the valve wheel 6 rests upon the upper surface of a stationary valve ring 15, the finish of the mating surfaces being such as to preclude passage of air therebetween while permitting relative movement. A single hole 16 extends through the valve ring 15 and is so disposed in relation to valve wheel 6 that the tim-

ing groove 13 of valve wheel 6 will pass over the center of the hole 16 as the valve wheel 6 is rotated. Interposed between the valve ring 15 and a ledge of the base 1 is a flexible diaphragm 17 which has a hole 18 in alignment with the hole 16 of the valve ring 15. As may be seen from Figures 6 and 7, the valve wheel 15 and the diaphragm 17 are fixedly mounted to the base 1 by means of dowels 19.

A tight seal is effected between the valve wheel 10 and the valve ring 15, and between the valve ring 15, diaphragm 17 and base 1 by a spring washer 21 which is interposed between a central hub on the cover 2 and the upper surface of the valve wheel 6.

Interconnecting the upper and lower chambers 10 and 20 of the valve base 1 are a pair of channels 21 and 22, the channel 21 cooperating with the hole 18 in the diaphragm 17, the channel 22 serving a purpose to be subsequently explained.

The central portion of the diaphragm 17 is provided with a pair of stiffening washers 23 disposed on opposite sides thereof and which surround a ferrule 24 of substantially rigid material which is provided through the center of the diaphragm 17. The lower portion of the ferrule 24 is provided with a thin, circular valve seat 25, a spring 26 being interposed between the ferrule 24 and the valve wheel 6 to bias the valve seat 25 into engagement with a valve disc 27 which, with an associated retainer, rests in a central recess in the valve base 1, as shown in Figure 2.

It will be seen that when the valve seat 25 is in contact with valve disc 27, no air may pass from the chamber 10 above the diaphragm 17 to the chamber 20 below that diaphragm except by the path through the channel 21, hole 16 and either hole 11 or the hole 11 and timing groove 13 depending upon the relationship between valve wheel 6 and valve wheel 15. On the other hand, when valve seat 25 is lifted from the valve disc 27, free access is provided for air flow through the open center of the ferrule 24 and channel 22.

The valve base 1 is rigidly mounted upon a main base 28. Interposed between the valve base 1 and the main base 28 so as to define the lower boundary of chamber 20 are a flexible diaphragm 29 and a sealing gasket 31. The central portion of the diaphragm 29 is provided with stiffening washers 32 at its opposite sides and a movable bracket 33 is connected thereto by means of a riveted or spun over element 34. The bracket 33 extends through a suitable hole 35 in the main base 28 and is fixedly mounted by screws 36 to a block 37. A spring 38 is interposed between the lower surface of the base 28 and the block 37 to bias the block 37 away from the base. The spring 38 surrounds a bossed section 39 of the base 28 carrying a guide pin 41 which projects through block 37 and into a suitable recess in a bumper 42, which is fixedly mounted to an armature lever 52, to be more fully described later.

The timing mechanism has been shown with an operator for an electric switch, shown generally at 43 as a self-contained electric switch of standard form having suitable cooperating switching contacts (not shown). The switch operator at 44 (Figure 1) is engaged by an adjustable abutment 45 mounted upon a member 57 pivoted to the main base 28 (Figure 8). An arm 46 extending from member 57 and having a sliding pivotal connection at 50 with the diaphragm block 37 by means of a pin and slot, also shown in Figure 8.

Associated with the timing mechanism in the

specific embodiment shown, there is an electromagnetic operator comprising an E-shaped field magnet 47 provided with an energizing coil 48 and adapted to attract a T-shaped armature member 49. The armature member 49 is pivotally mounted at 51 to the aforementioned armature lever 52. The armature lever 52 has an upstanding flange 53 slidably disposed within slots in upper guide plates 54 which are in turn rigidly mounted on a mounting plate 55. An armature guide plate 56, together with the guide plates 54, confine the operating path of the armature lever 52 to vertical, reciprocating motion.

A strong reset spring 59 is interposed between the armature lever 52 and the base 28 to bias the parts into the position illustrated in Figure 2.

To the front of armature guide plate 56 is mounted an electrical interlock 61 having an operator 62 disposed so as to be reciprocated by an extension 63 of the armature lever 52.

The operation of the timing relay is as follows:

Energization of the solenoid 43 causes armature 49 to move downwardly against the bias of the reset spring 59. Armature 49 carries armature lever 52 downwardly carrying therewith the bumper 42. As bumper 42 moves away from diaphragm block 37, spring 38 will tend to move diaphragm block 37, and the bracket 33 on which it is mounted, downwardly. The rate of this downward movement is dependent upon the rate of movement of diaphragm 17, to which bracket 33 is also attached. With the valve wheel 6 in the position illustrated in Figure 2, air will pass through the holes 3 in cover 2, filter 4, directly through the hole 11 in valve wheel 6 and the hole 16 in valve disc 15, hole 18 in diaphragm 17 and through channel 21 to the chamber 20 above diaphragm 29, which will therefore rapidly move downwardly under the bias imparted thereto by spring 38. Downward movement of diaphragm block 37 will effect rotation of the arm 46 and member 57 to thereby effect operation of the switch mechanism 43. Downward movement of the extension 63 of the armature lever 52 is always without delay to effect immediate operation of the electrical interlock 61. It should be noted that the position of parts of Figure 2 will produce the minimum timed period.

When, on the other hand, the valve wheel 6 is rotated (as, for example, to the position of Figure 9) so that a portion of the timing groove 13, rather than the hole 11, is over the hole 16 in the valve wheel 15, when diaphragm 29 is urged downwardly by bracket 33 under bias of spring 38, timing air will pass through the hole 11 into the timing groove 13 to the hole 16 and then through holes 16 and 18 and channel 21 into the chamber 20. As earlier indicated, the engaging surfaces of the valve wheel 6 and the valve ring 15 are so finished that air is excluded from the timing groove 13 everywhere except through the hole 11 in the valve wheel. It will, therefore, be seen that by rotation of the valve wheel 6, the timing air will leave the timing groove at any selected point in its length. Inasmuch as the frictional resistance to the flow of air through capillary timing groove 13 is so large that the rate at which the air flows is directly proportional to the length of the path through which it must flow, the rate at which air is permitted to enter the chamber 20 above the diaphragm 29 is directly dependent upon the effective length of the timing groove. That is to say the length of the timing groove through which the incoming air must pass directly determines the rate at which

air enters the diaphragm chamber. Hence, as wheel 6 is rotated to vary the length of groove 13 between holes 11 and 16, the timing period will proportionally and "steplessly" vary.

It should also be noted that with the valve wheel 6 so positioned that the flat surface of wheel 6 between the hole 11 and the depression 14 covers the hole 16 of the valve disc 15, no air whatsoever would be permitted to enter the chamber 20, which therefore could not expand regardless of energization of the coil 48. With such a setting the timing unit may be readily tested for leaks.

Upon deenergization of the coil 48, the reset spring 59 rapidly returns the armature 49 toward the position of Figure 2. Bumper 42 strikes the lower surface of diaphragm block 37 forcing it upwardly and compressing the spring 38. This return movement is rapidly effected as the air in chamber 20 will be exhausted through the channel 22 and, acting upon the large area of the diaphragm 17 will lift the valve seat 25 from the valve disc 27, the air thereby being admitted to the space above the diaphragm 17 and escaping to the outer atmosphere through the felt filter 4 and the holes 3 of the cover 2. After this air has been forced out, the valve seat 25 recloses upon the valve disc 27 under the bias of spring 26. It will be seen that due to the large effective area of the diaphragm 17, the force required to open the valve is very small. Further, the large area of the diaphragm 17 also serves to cause a relatively large force to be exerted by the small valve seat 25 upon the valve disc 27 during the timing period when the chamber 20 above the diaphragm 29 is under a partial vacuum.

It will be seen that for any setting of the dial 8 and the associated valve disc 6, the rate at which fluid can pass into the chamber above the diaphragm 29 to permit its downward movement is directly dependent upon the length of the timing groove 3 through which the timing air must pass. It will further be seen that the timing period is unaffected in any way by backlash in the device, the timing period being exactly the same at any predetermined setting of the valve wheel 6, regardless of the direction of rotation of the valve wheel to reach that setting.

It is obvious that the materials from which the valve wheel 6 and the valve ring 15 are made must be such that a solid, smooth finish may be placed upon the mating surfaces thereof; furthermore, these surfaces should be corrosion resistant and any "sticking" tendency should be minimum. While many substances may be employed, as a specific example a valve wheel of die cast aluminum with a valve ring of either nickel-silver or a non-metallic material have been found to be suitable.

It will further be seen that the timing groove 13 could be cut in the valve ring 15, instead of in the valve wheel 6 as illustrated, without changing the characteristics of the device.

Referring to Figures 10 and 11, there are illustrated therein two modifications of the timing groove to achieve special timing characteristics. In Figure 10, for example, there is shown a valve wheel 106 (similar to wheel 6 already described) having a tapered timing groove 113 cut therein which terminates in a hole 111 extending through wheel 106. In Figure 11 there is illustrated a valve wheel 206 (also similar to wheel 6) in which a "stepped" timing groove 213 is cut, groove 213 terminating in hole 211 extending through wheel 206. Both of these modified timing grooves, as

well as others which those skilled in the art will readily perceive, will produce special relationships between timing periods and setting movements which may be desired, for example to expand the movement and scale at certain ranges.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a timing device comprising a variable volume chamber and means movable to change said chamber volume and effect a control function, means for controlling the rate of movement of said movable means to determine a timed period comprising, a pair of relatively movable members each having both an aperture extending therethrough and at least one flat surface, a capillary groove in one of said surfaces, said groove communicating with one of said apertures, the other of said apertures communicating with any and all selected portions of said groove, means maintaining said surfaces in close engagement, means for moving one of said relatively movable members to effect a sliding movement between said flat surfaces, and thereby positioning a stepless, continuously varying length of said capillary groove between said apertures.

2. In a timing device comprising a variable volume chamber and means movable to change said chamber volume and effect a control function, means for controlling the rate of movement of said movable means to determine a timed period comprising, a rotatable member and a fixed member each having both an aperture extending therethrough and at least one flat surface, a capillary groove in the flat surface of said rotatable member, said groove being symmetrically disposed about the axis of rotation of said rotatable member, the aperture in said rotatable member communicating with one portion of said capillary groove, the aperture in said fixed member being positioned to communicate with said capillary groove, means maintaining said flat surfaces in close engagement, and means for rotating said rotatable member to effect a sliding movement between said flat surfaces and a progressively changing relationship between said two apertures, whereby a continuously varying length of said capillary groove may be positioned between said apertures.

3. In a timing device comprising a variable volume chamber and means movable to change said chamber volume and effect a control function, means for controlling the rate of movement of said movable means to determine a timed period comprising, a pair of relatively movable members each having both an aperture extending therethrough and at least one flat surface, a capillary groove in one of said surfaces, said groove communicating with one of said apertures, the other of said apertures communicating with any and all effective portions of said groove as desired, means maintaining said surfaces in close engagement, means for moving one of said relatively movable members to effect a sliding movement between said flat surfaces, and means for positioning a stepless, continuously varying length of said capillary groove between said apertures, said capillary groove being of constant cross sectional area throughout its length whereby a linear relationship between the timed period and the

length of said groove between said apertures exists.

4. In a timing device comprising a variable volume chamber and means movable to change said chamber volume and effect a control function, means for controlling the rate of movement of said movable means to determine a timed period comprising, a rotatable member and a fixed member each having both an aperture extending therethrough and at least one flat surface, a capillary groove in the flat surface of said rotatable member, said groove being symmetrically disposed about the axis of rotation of said rotatable member, the aperture in said rotatable member communicating with one portion of said capillary groove, the aperture in said fixed member being positioned to communicate with said capillary groove, means maintaining said flat surfaces in close engagement, and means for rotating said rotatable member to effect a sliding movement between said flat surfaces and a progressively changing relationship between said two apertures, whereby a continuously varying length of said capillary groove may be positioned between said apertures, said capillary groove being of constant cross sectional area throughout its length to provide a linear relationship between the timed period and the length of said groove between said apertures.

5. In a timing device comprising a variable volume chamber and means movable to change said chamber volume and effect a control function, means for controlling the rate of movement of said movable means to determine a timed period comprising, a rotatable member and a fixed member each having both an aperture extending therethrough and at least one flat surface, a capillary groove in the flat surface of one of said members, said groove being symmetrically disposed about the axis of rotation of said rotatable member, one of said apertures communicating with said groove and the other of said apertures communicating with selected portions of said groove, means maintaining said surfaces in close engagement, and means for rotating said rotatable member to effect a sliding movement between said flat surfaces and position a continuously varying length of said groove between said apertures.

6. In a timing device comprising a variable volume chamber and means movable to change said chamber volume and effect a control function, means for controlling the rate of movement of said movable means to determine a timed period comprising, a rotatable member and a fixed member each having both an aperture extending therethrough and at least one flat surface, a capillary groove in the flat surface of one of said members, said groove being symmetrically disposed about the axis of rotation of said rotatable member, one of said apertures communicating with said groove and the other of said apertures communicating with selected portions of said groove, means maintaining said surfaces in close engagement, and means for rotating said rotatable member to effect a sliding movement between said flat surfaces and position a continuously varying length of said groove between said apertures, said capillary groove being of constant cross sectional area throughout its length to provide a linear relationship between the timed period and the length of said groove between said apertures.

7. In a timing device comprising a variable volume chamber and means movable to change

5 said chamber volume and effect a control function, means for controlling the rate of movement of said movable means to determine a timed period comprising, a rotatable member and a fixed member each having both an aperture extending therethrough and at least one flat surface, a capillary groove in the flat surface of one of said members, said groove being symmetrically disposed about the axis of rotation of said rotatable member, one of said apertures communicating with said groove and the other of said apertures communicating with selected portions of said groove, means maintaining said surfaces in close engagement, and means for rotating said rotatable member to effect a sliding movement between said flat surfaces and position a continuously varying length of said groove between said apertures, said capillary groove being of progressively varying cross-sectional area to provide an exponential relationship between the timed period and the length of said groove between said apertures.

8. In a timing device comprising a variable volume chamber and means movable to change said chamber volume and effect a control function, means for controlling the rate of movement of said movable means to determine a timed period comprising, a rotatable member and a fixed member each having both an aperture extending therethrough and at least one flat surface, a capillary groove in the flat surface of one of said members, said groove being symmetrically disposed about the axis of rotation of said rotatable member, one of said apertures communicating with said groove and the other of said apertures communicating with selected portions of said groove, means maintaining said surfaces in close engagement, and means for rotating said rotatable member to effect a sliding movement between said flat surfaces and position a continuously varying length of said groove between said apertures, said capillary groove being of one cross-sectional area over a portion of its length and a different cross-sectional area over the remaining portion of its length to vary the relationship between the change in the timed period and the change in the length of said groove disposed between the apertures.

9. In a timing device, a chamber, means movable to effect expansion and contraction of the volume of said chamber, means biasing said first mentioned means for movement in one direction, means for moving said first mentioned means in the opposite direction against said biasing means, means for providing free passage of air from said chamber as said movable means moves in one direction, and means for varying the rate of air flow into said chamber as said movable means is moved in another direction for determining the timed period, said last mentioned means comprising a pair of relatively movable members each having both an aperture extending therethrough and at least one flat surface, a capillary groove in one of said surfaces, and means maintaining said flat surfaces in close engagement, one of said apertures communicating one portion of said groove with said chamber and the other aperture communicating one portion of said groove with the atmosphere, movement of one of said relatively movable members effecting a sliding movement between said flat surfaces and a progressively changing relationship between said two apertures whereby a continuously varying length of said capillary groove is positioned between the atmosphere and said chamber.

10. In a timing device, a chamber, means movable to effect expansion and contraction of the volume of said chamber, means biasing said first mentioned means for movement in one direction, means for moving said first mentioned means in the opposite direction against said biasing means, means providing free passage of air from said chamber as said movable means moves in one direction, and means for varying the rate of air flow into said chamber as said movable means is moved in another direction for determining the timed period, said last mentioned means comprising a pair of relatively movable members each having both an aperture extending therethrough and at least one flat surface, a groove in one of said surfaces having a progressively varying cross sectional area, and means maintaining said flat surfaces in close engagement, one of said apertures communicating one portion of said groove with said chamber and the other aperture communicating one portion of said groove with the atmosphere, movement of one of said relatively movable members effecting a sliding movement between said flat surfaces and a progressively changing relationship between said two apertures whereby a continuously varying length of said groove is positioned between the atmosphere and said chamber.

11. In a timing device, a chamber, means movable to effect expansion and contraction of the volume of said chamber, means biasing said first mentioned means for movement in one direction, means for moving said first mentioned means in the opposite direction against said biasing means, means for providing free passage of air from said chamber as said movable means moves in one direction, and means for varying the rate of air flow into said chamber as said movable means is moved in another direction for determining the timed period, said last mentioned means comprising a pair of relatively movable members each having both an aperture extending therethrough and at least one flat surface, a groove in one of said surfaces, said groove having one cross sectional area over a portion of its length and a different cross sectional area over the remaining portion of its length, and means maintaining said flat surfaces in close engagement, one of said apertures communicating one portion of said groove with said chamber and the other aperture communicating one portion of said groove with the atmosphere, movement of one of said relatively movable members effecting a sliding movement between said flat surfaces and a progressively changing relationship between said two apertures whereby a continuously varying length of said groove is positioned between the atmosphere and said chamber.

12. In a timing device, a chamber, means movable to effect expansion and contraction of the volume of said chamber, means biasing said first mentioned means for movement in one direction, means for moving said first mentioned means in the opposite direction against said biasing means, means for providing free passage of air from said chamber as said movable means moves in one direction, and means for varying the rate of air flow into said chamber as said movable means is moved in another direction for determining the timed period, said last mentioned means comprising a fixed and a movable member each having both an aperture extending therethrough and at least one flat surface, a capillary groove in the flat surface of said movable member, and means maintaining said flat surfaces in close en-

gagement, the aperture in said movable member communicating one end of said capillary groove with the atmosphere, the aperture in said fixed member communicating said capillary groove with said chamber, movement of one of said movable members effecting a sliding movement between said flat surfaces and a progressively changing relationship between said two apertures whereby a continuously varying length of said capillary groove is positioned between the atmosphere and said chamber.

13. In a timing device, a chamber, means movable to effect expansion and contraction of the volume of said chamber, means biasing said first mentioned means for movement in one direction, means for moving said first mentioned means in the opposite direction against said biasing means, means for providing free passage of air from said chamber as said movable means moves in one direction, and means for varying the rate of air flow into said chamber as said movable means is moved in another direction for determining the timed period, said last mentioned means comprising a fixed and a rotatable member each having both an aperture extending therethrough and at least one flat surface, a capillary groove in the flat surface of said rotatable member, said groove being symmetrically disposed about the axis of rotation of said rotatable member, and means maintaining said flat surfaces in close engagement, the aperture in said rotatable member communicating one portion of said capillary groove with the atmosphere, the aperture in said fixed member being positioned to communicate said capillary groove with said chamber, rotation of said rotatable member effecting a sliding movement between said flat surfaces and a progressively changing relationship between said two apertures whereby a continuously varying length of said capillary groove is positioned between the atmosphere and said chamber.

14. In a timing device, a chamber, means movable to effect expansion and contraction of the volume of said chamber, means biasing said first mentioned means for movement in one direction, means for moving said first mentioned means in the opposite direction against said biasing means, means for providing free passage of air from said chamber as said movable means moves in one direction, and means for varying the rate of air flow into said chamber as said movable means is moved in another direction for determining the timed period, said last mentioned means comprising a fixed and a rotatable member each having both an aperture extending therethrough and at least one flat surface, a capillary groove in the flat surface of said rotatable member, said groove extending in an arcuate path symmetrically about the center of rotation of said movable member, resilient means maintaining said flat surfaces in close engagement, an upstanding shaft projecting from said rotatable means, a dial mounted to said shaft for rotation therewith, and an indicia bearing chart mounted to said dial, one of said apertures communicating one portion of said groove with said chamber and the other aperture communicating one portion of said groove with the atmosphere, rotation of said dial effecting rotation of said rotatable member whereby a sliding movement between said flat surfaces occurs and a progressively changing relationship between said two apertures is effected so that a continuously varying length of said capillary groove is positioned between the atmosphere and said chamber.

15. In a timing device, a chamber, means movable to effect expansion and contraction of the volume of said chamber, and means for varying the rate of air flow into said chamber as said movable means is moved in one direction for determining the timed period including a pair of relatively movable members each having both an aperture extending therethrough and at least one flat surface, a capillary groove in one of said surfaces, and means maintaining said flat surfaces in close engagement, one of said apertures communicating one portion of said groove with said chamber and the other aperture communicating one portion of said groove with the atmosphere, movement of one of said movable members effecting a sliding movement between said flat surfaces and a progressively changing relationship between said two apertures whereby a continuously varying length of said capillary groove is positioned between the atmosphere and 15 said chamber, and means responsive to movement of said movable means for effecting a control function.

16. In a timing device, a chamber, means movable to effect expansion and contraction of the volume of said chamber, and means for varying the rate of air flow into said chamber as said movable means is moved in one direction for

determining the timed period including a fixed and a rotatable metal disc, each having both an aperture extending therethrough and at least one flat surface, a capillary groove in the flat surface of said rotatable disc having one end communicating with the aperture therein, said capillary groove extending in a symmetrical arcuate path about the center of rotation of said rotatable member, means mounting and maintaining said discs with the flat surfaces in close engagement and with the aperture in said fixed disc communicating said groove with said chamber, rotation of said rotatable disc effecting a sliding movement between said flat surfaces and a progressively changing relationship between said two apertures whereby a continuously varying length of said capillary groove is positioned between said apertures, and means responsive to movement of said movable means for effecting a control function.
